[57] CLAIM

The ornamental design for a chair, as shown and described.

DESCRIPTION

FIG. 1 is a front perspective view of one embodiment of a chair showing my design;

FIG. 2 is a rear perspective view of the chair shown in FIG. 1;

FIG. 3 is a front perspective view of another embodiment of the chair showing my design;

FIG. 4 is a rear perspective view of the chair shown in FIG. 3;

FIG. 5 is a front perspective view of the back rest cushion of the chair shown in FIG. 1;

FIG. 6 is a rear perspective view of the back rest cushion shown in FIG. 5;

FIG. 7 is a bottom perspective view of a seat cushion for the chair shown in FIG. 1; and,

FIG. 8 is a top perspective view of the seat cushion shown in FIG. 7.

The cushions shown in FIGS. 5 through 8 have been shown without the remainder of the chair for ease of illustration. The broken lines shown on the cushions in FIGS. 5 through 8 represent stitching.
